UNITED STATES PATENT OFFICE.

DAVID W. BOARDMAN, OF LOS ANGELES, CALIFORNIA.

LADDER.

Application filed January 7, 1926. Serial No. 79,863. Renewed February 16, 1928.

This invention relates to an attachment for the sections of an extensible ladder, whereby an extensible ladder may be readily converted into an A-type ladder.

5 One of the important objects of the present invention is to provide an attachment for the upper ends of the sections of the extensible ladder which cooperates to provide a hinge to facilitate the formation of 10 an A-type ladder, said means further forming a lock to hold the A-type ladder in its assembled position against accidental collapsing.

A further object is to provide an attachment 15 of the above mentioned character which may be readily and easily secured on the ladder sections, the same being of such construction as to act as a guide when the ladder sections are moved to an extended or 20 lowered position.

A still further object is to provide a device of the above mentioned character which is simple in construction, inexpensive, strong and durable, and further well adapted to 25 the purpose for which it is designed.

Other objects and advantages of the invention will become apparent during the course of the following description taken in connection with the accompanying drawings.

30 In the accompanying drawings forming part of this application and in which like numerals designate like parts throughout the same:

Figure 1 is a fragmentary enlarged side 35 elevation of the upper ends of the ladder sections showing my improved attachment associated therewith, the parts being arranged in such a manner as to form a lock for holding the ladder sections in their A-type formation.

Figure 2 is a front edge elevation of the attachment as associated with the upper ends of the ladder sections.

Figure 3 is a rear edge elevation.

45 Figure 4 is a side elevation of the means provided for holding the ladders against downward sliding movement when disposed in their extensible positions.

Figure 5 is an edge elevation thereof.

50 Figure 6 is a view similar to Figure 1 showing the A-type ladder in its locked position.

Figure 7 shows the position of the parts comprising the attachment when the ladder sections are disposed in abutting relation

and previous to the sliding of the sections with respect to each other.

Figure 8 is a similar view showing the arrangement of the parts when the ladder sections are being extended with respect to each other.

Figure 9 is a detail perspective view of one of the notched plates, and

Figure 10 is a similar view of the cooperating member.

In the drawings, wherein for the purpose of illustration is shown the preferred embodiment of my invention, the numerals 1 and 2 designate generally a pair of complementary ladder sections, which are 70 adapted to form either an extensible ladder, or a ladder of the A-type in the manner hereinafter to be more fully described.

My attachment includes a metallic plate 3 which is adapted to be secured on the inner face of each of the side rails of the ladder section 1 at a point adjacent the upper end thereof. The rear end of each plate is provided with the angularly disposed portion 4 which engages the rear edge of the respective side rail and is adapted to be secured thereto by suitable fastening screws shown at 5. A suitable opening 6 is formed in the intermediate portion of the plate and through which is 80 adapted to extend suitable fastening means shown at 7 which fastening means extends through the respective side rails of the ladder section 1.

The plate 3 has its forward end projecting beyond the forward edge of each side rail of the ladder section 1 in the manner as clearly illustrated in Figures 1 and 7, the forward edge of the plate 3 being curved and having its lower portion cut away as 85 indicated at 8. A diagonally arranged slot 9 is formed in the upper forward portion of the plate 3, the same extending from the upper edge of the plate to a point adjacent the intermediate portion thereof and as is clearly shown in the drawings, the upper portion of the slot is relatively wide for a purpose which will be readily obvious. This diagonally arranged slot 9 merges or communicates with an additional diagonally disposed slot 10 which is disposed in a rearward direction. The lower rear portion of the last mentioned diagonal slot 10 is cut away as at 11 so that the lower portion of the diagonal slot 10 will be relatively wider 110

than the upper portion of said slot. At the juncture of the diagonally disposed slots 9 and 10, the respective sides of the slots are cut away so that a relatively wide entrance 5 to the slots 10 will be provided. This construction is more clearly illustrated in Figure 8.

Secured on the inner face of each of the side rails of the complementary ladder section 2 at a point adjacent the upper end thereof is the substantially rectangular plate 12, the same being provided with the openings 13 for receiving the securing means which is to be driven into the respective 10 side rails of the ladder section 2. The upper rear end of the plate 12 has extending laterally therefrom the flat arm 14, and for the purpose of convenience, the same is termed a pintle. As is clearly illustrated in 15 the several figures of the drawing, this pintle is disposed at an oblique angle, and is adapted for cooperation with the diagonally disposed slots 9 and 10 in the manner to be presently apparent.

25 A substantially U-shaped guide member 15 has its crown portion 16 extending transversely across the outer face of each of the side rails of the ladder section 1 at a point above the plate 3 so that the arms 17 and 30 18 of the U-shaped member extend transversely across the front and rear edges of the side rails of the ladder sections as clearly illustrated in Figures 2 and 3. As further illustrated in Figures 2 and 7 of 35 the drawings, the crown or base portion 16 of the U-shaped guide member 15 is secured to the outer face of the respective side rails of the ladder section 1 so that the arm 18 will lie flush against the rear edge of the 40 respective side rail of the ladder section 1, thus spacing the other arm 17 with respect to the forward edge of the rail of the section 1 for a purpose also to be presently apparent. The securing means for the U-shaped guide member 15 is shown at 19.

45 As shown more clearly in Figure 2, the pintle 14 which is formed on the upper rear portion of the plate 12 is of such width as to have its outer edge spaced from the outer 50 face of the respective side rails of the ladder section 1 so that the U-shaped guide 15 will not interfere with the sliding movement of the pintle through the guide.

The inner face of each of the side rails 55 of the ladder section 2, which section is of less width than the section, has secured thereon in a pivoted manner, the rung engaging member 20. As this member is of the usual construction, and is further well known in the art, a further detailed description thereof is not thought necessary.

60 It is understood of course that the member is adapted to straddle the adjacent rungs A and B of the ladder sections 1 and 2 65 respectively for the purpose of limiting the

downward sliding movement of the section 2 with respect to the section 1. This member is used on ladders of the extensible type and as the same forms no important part of the present invention, a further discussion thereof is not thought necessary.

When an A-type ladder is to be formed, the ladder sections 1 and 2 are disposed in the position as shown in Figures 1 and 6, and when in this position it will be readily 75 seen that the pintle 14 will have its upper and lower edges engaging the upper and lower edges of the diagonal slot 10 of the respective plates 3, so that a lock will be provided at the upper end of the ladder 80 sections between the cooperating elements secured to the upper portions of the side rails of the ladder sections thereby holding the ladder in its A-type formation against accidental collapsing.

85 When it is desired to convert the ladder from an A-type structure to an extensible ladder, the ladder sections are brought together to the position shown in Figure 7, thus disengaging the upper and lower edges 90 of the pintle from engagement with the upper and lower edges respectively of the diagonal slot 10 so that the lower edge of the pintle will be disposed within the cut away portion 11. The ladder section 2 is then 95 moved laterally with respect to the section 1 so that the obliquely disposed pintle 14 will be in alignment with the diagonal slot 9 and when the parts are so arranged, the section 2 is then moved upwardly, causing 100 the pintle 14 to pass upwardly through the diagonal slot 9 in the manner shown more clearly in Figure 8, so as to cause the pintle to be disengaged from the forward end of the respective plate.

105 As the outer edge of the pintle is spaced from the crown portion 16 of the U-shaped guide 15, the same will be free to pass upwardly through the U-shaped guide as the section 2 is moved upwardly. The U-shaped guide 15 will have its arms cooperating with the side rails of the section 2 in maintaining the same in proper position with respect to the section 1 during the upward sliding movement of the section 2. As 115 heretofore stated, the member 20 will cooperate in securing the complementary ladder section against downward sliding movement when the sections have been extended to their proper length.

120 It will thus be seen from the foregoing description, that a highly novel and simple means has been provided which may be readily and easily attached to a pair of complementary ladder sections to enable said sections to either form an A-type ladder or an extensible ladder.

125 The simplicity in which my improved attachment is constructed further more enables the same to be secured on the ladder 130

sections without necessitating any alterations of the sections and will furthermore be strong and durable.

While I have shown the preferred embodiment of my invention it is to be understood that minor changes in the size, shape and arrangement of parts may be resorted to without departing from the spirit of the invention and the scope of the appended 10 claim.

Having thus described the invention, what I claim as new is:—

In combination with a pair of ladder sections, of cooperating means associated with 15 the upper ends thereof to provide a hinge whereby the ladder sections are adapted to form an A-type ladder, said means further acting as a lock to prevent the accidental collapsing of the A-type ladder, the aforementioned means comprising a plate secured 20 on the inner face of each side rail of one of the ladder sections, the forward portion of the plate projecting beyond the forward edge of the respective side rail and being 25 provided with a diagonally disposed slot which extends downwardly from the upper forward edge of the plate, the forward por-

tion of the plate being further provided with an additional diagonally rearwardly disposed slot, the same being disposed at an 30 angle with respect to the aforementioned diagonal slot and communicating therewith, the lower rear portion of the last mentioned slot being wider than the upper portion thereof, the respective sides of the slots being cut away at the juncture of said slots to provide a relatively wide entrance to the last mentioned diagonally disposed slot, an additional plate secured to the inner face 40 of each of the side rails of the complementary ladder section, an obliquely disposed pintle extending laterally from said last mentioned plate, said pintle adapted to pass through the first mentioned diagonal slot when the ladder sections are arranged in a 45 predetermined manner, the ladder sections being further locked in A-type formation when the pintle is disposed in the last mentioned diagonal slots in a predetermined manner. 50

In testimony whereof I affix my signature.

DAVID W. BOARDMAN.
